UNITED STATES PATENT OFFICE.

EVERETT A. WILLIAMS AND ALBERT H. WARD, OF LOS ANGELES, CALIFORNIA.

ORE-CONCENTRATOR.

1,356,249.

Specification of Letters Patent. Patented Oct. 19, 1920.

Application filed April 3, 1919. Serial No. 287,268.

To all whom it may concern:

Be it known that we, EVERETT A. WILLIAMS and ALBERT H. WARD, citizens of the United States, residing at Los Angeles, in the county of Los Angeles and State of California, have invented new and useful Improvements in Ore-Concentrators, of which the following is a specification.

Our invention relates to ore concentrators and consists of the novel features herein shown, described and claimed.

Figure 1 is a side elevation of an ore concentrator embodying the principles of our invention as seen looking in the direction indicated by the arrow 1 in Fig. 2.

Fig. 2 is a top plan view looking in the direction indicated by the arrow 2 in Fig. 1.

Fig. 3 is a vertical cross section upon an enlarged scale and upon the lines 3—3 of Figs. 1 and 2 and looking in the direction indicated by the arrows.

Fig. 4 is a fragmentary horizontal section upon a reduced scale and upon the line 4—4 of Fig. 3.

Fig. 5 is a fragmentary cross section on the line 5—5 of Fig. 1.

Fig. 6 is a fragmentary vertical longitudinal sectional detail on the line 6—6 of Figs. 2 and 3.

The platform 1 may be constructed of any suitable material and of any suitable size. Posts 2, 3, 4 and 5 are fixed vertically upon the platform 1, and each of the posts has braces 6 and 7 extending forwardly and backwardly. A crosspiece 8 connects the upper ends of the posts 2 and 5, and a crosspiece 9 connects the upper ends of the posts 3 and 4. An adjusting screw 10 is mounted vertically through the center of the crosspiece 8, and a similar adjusting screw 11 is mounted vertically through the center of the crosspiece 9.

The ore concentrator box 12 is rectangular in plan and has a flat bottom 13, straight sides 14 and 15, a head end 16, and a discharge end 17. The discharge end 17 is normally open. Cleats 18 and 19 are secured to the inner face of the extreme rear end of the side 15, and similar cleats 20 and 21 are secured to the inner face of the extreme rear end of the side 14 to make slideways for the end gates 22, said end gates 22 being narrow strips fitting in the slideways across the bottom 13 one on top of the other.

Rollers 23 and 24 are mounted in brackets

25 and 26 secured to the lower face of the bottom 13, so that the rollers will travel crosswise of the box. A timber 27 fits upwardly against the rollers 23 and 24, the ends of the timber extending beyond the sides of the box. Rods 28 and 29 extend through the ends of the timber 27 and upwardly through a second timber 30, and the adjusting screw 11 extends through a screw threaded nut plate 31 fixed upon the cross-piece 9 and through the center of the second timber 30 and has a bearing 32 upon its lower end below the timber 30 so as to support the rear end of the box, and so that by manipulating the handwheel 33 upon the screw 11 the rear end of the box may be raised or lowered.

In a like manner the forward end of the box is mounted upon rollers resting upon a timber connected to the adjusting screw 10 to be manipulated by the handwheel 34 so that the rear end of the box may be raised or lowered by manipulating the handwheel 34.

Cleats 35 and 36 (see Fig. 4) are secured to the inner face of the post 3 to make a vertical slideway, and similar cleats 37 and 38 are secured to the inner face of the post 4 to make a second vertical slideway, and the ends of the timbers 27 and 30 fit between the cleats so as to guide the timbers up and down. In a like manner the timbers supporting the forward end of the box are guided up and down between the posts 2 and 5. A crosspiece 39 is rigidly mounted between the posts 3 and 4 some distance below the box, and a similar crosspiece 40 is rigidly mounted between the posts 2 and 5. A cam shaft 41 is mounted in bearings 42 and 43 upon the crosspieces 40 and 39. Eccentric cams 44 and 45 are fixed upon the cam shaft 41. Cam brackets 46 and 47 are fixed to the bottom 13 of the box 12 and extend downwardly to engage the eccentric cams 44 and 45. The cam bracket 47 consists of two vertical parallel arms 48 and 49 long enough to allow the box 12 to go up and down to the desired extent, and the eccentric cam 45 fits between these arms, so that as the shaft rotates the box 12 is reciprocated transversely.

The brackets 25 and 26 and the rollers 23 and 24 are adapted to travel transversely of the frame and to engage the timbers 27 to hold the box from reciprocating endwise.

- The cam bracket 46 is similar to the cam bracket 47. A knuckle joint 50 is connected to the forward end of the cam shaft 41, an extension shaft 51 is connected to the 5 knuckle joint 50, a second knuckle joint 52 is connected to the extension shaft 51, a second extension shaft 53 is connected to the knuckle joint 52, a worm gear transmission 54 is connected to the second extension shaft 53, and 10 a motor 55 is mounted upon the platform 1, and the motor shaft is connected to the worm gear transmission 54 by a shaft 56, so that as the motor operates the box 12 is reciprocated transversely of the frame. 15 Gear racks 57, 58, 59 and 60 are fixed to the platform 1, segmental gears 61, 62, 63 and 64 fit upon the gear racks, arms 65, 66, 67 and 68 are secured to the segmental gears, downwardly inclined notches 69 and 20 70 are formed from the forward edges of the arms 68 and 67, and similar notches are formed from the forward edges of the arms 65 and 66. The reciprocating frame 71 has side bars 72 and 73, and end bars 74 and 75 25 connecting the ends of the side bars. Studs 76 and 77 extend from the side bar 73 into the notches 69 and 70, and similar studs extend from the side bar 72 into the notches in the arms 65 and 66 so as to support the 30 frame 71 in a horizontal position above the box 12. Notches 78 and 79 are formed in the arms 68 and 67 near their upper ends, and similar notches are formed in the arms 65 and 66, so that the frame 71 may be 35 raised and the stud 76 and 77 placed in the notches of the arms 65 and 66 and in the notches 78 and 79 of the arms 67 and 68 to hold the frame elevated from the box 12 when the box is being cleaned. 40 A link 80 connects the upper end of the arm 65 to a crank 81 carried by the crank shaft 82 mounted in a bearing 83 upon the upper ends of the posts 84 and 85. A large belt wheel 86 is fixed upon the crank shaft 45 82, and a belt 87 connects the large belt wheel to a small belt wheel 88 upon the shaft 56, so that as the motor 55 operates the frame 71 is reciprocated longitudinally in a horizontal plane. The segmental gears 50 61, 62, 63 and 64 are concentric to the studs 76 and 77, so that as the arms 65, 66, 67 and 68 vibrate the frame 71 travels in a horizontal plane.
- A plurality of rakes 89 is mounted between the side bars 72 and 73 and extend downwardly into the box 12. Each rake 89 consists of attaching plates 90 and 91 fitting against the inner faces of the side bars 73 and 72, spacing arms 92 and 93 extending inwardly from the inner ends of the attaching plates 90 and 91 over the upper edges of the sides 14 and 15 and downwardly, the head 94 connecting the lower ends of the spacing arms 92 and 93, 65 and spikes 95 driven downwardly through

the head 94. The spikes 95 are evenly spaced apart and of even length so as to pass freely above the bottom 13.

A plurality of impellers 96 is mounted crosswise of the frame 71, there being an 70 impeller 96 in front of each rake 89. Each impeller 96 comprises a shaft 97 fixed with its ends in the side bars 73 and 72, spacing collars 98 and 99 upon the shaft, and a plurality of paddles 100 arranged alternately 75 with the plurality of spacing collars 101. The paddles 100 are preferably arranged to come in planes between the longitudinal planes of the rake teeth 95.

Each paddle 100 comprises a flat piece 80 of strap iron cut and bent to form a blade 102, and an elongated eye 103 fitting loosely upon the shaft 97. The shaft 97 is mounted above the head 94, so that the blade 102 may swing to a vertical position against 85 the front face of the head 94 when the frame 71 is moving backwardly and to swing freely away from the head 94 when the frame 71 is moving forwardly.

The parts 57 to 103 constitute the reciprocating agitator and impeller 104. The ore box 12 extends forwardly beyond the front end of the reciprocating agitator and impeller 104 to form the feed space 105.

The ore concentrator thus constructed 95 should be mounted or adjusted so that the ore box 12 is substantially level. The ore bearing dirt may be placed in the feed space 105 in several ways. If the dirt is handled dry to the concentrator it may be shoveled 100 into the space 105 by hand, and if the ore is being handled from a mill it may be discharged in the form of slop or sludge from a pipe.

The concentrator is designed especially 105 for use in isolated places as upon a desert place where there is no mill, where the ore is to be handled in comparatively small quantity, and where water is an important item. Sufficient water must be supplied to the box 12 in proportion to the ore to make 110 a sloppy mass. When the motor is started the slop will be agitated by the transverse reciprocation of the box 12 and the longitudinal reciprocation of the agitator and impeller 104, and at the start the adjusting screws 10 and 11 will be manipulated to bring the rake teeth 95 near the upper face of the bottom 13, and as the concentrator continues to operate the rake teeth will 120 break up the lumps and stir up the mass, and the impeller blades 102 will move the upper part of the mass backwardly leaving the ore values to settle upon the bottom 13. The lower ends of the blades 102 are above 125 the lower ends of the teeth 95, so that the blades will move the upper part of the mass backwardly and not disturb the settled lower part of the mass. Water and ore will be added to the box gradually and the 130

water carrying the mud and waste material will flow over the gate 22 while the ore values settled upon the bottom 13 will not flow over the gate. As the depth of the 5 ore increases the handwheels 33 and 34 will be manipulated to lower the box and an additional gate 22 will be added from time to time.

The last row of paddles 106 have their 10 blades 107 cut shorter than the blades of the other rows, so that these blades 107 will pass just over the top of the gate 22 to keep the gate clean, that is clear of obstructions which would interfere with the even flow 15 of muddy water.

The swinging action of the blades 102 serves to advance the mud toward the rear end and alternately discharge the mud over the gate.

20 When the mass of ore values in the box 12 has been increased to the desired depth the agitator and impeller 104 is raised bodily to bring the studs 76 and 77 into the notches 78 and 79 and then the ore may 25 be shoveled out of the box.

Various changes may be made without departing from the spirit of our invention as claimed.

We claim:

30 1. An ore concentrator comprising an ore box having a feed end and a discharge end, means for reciprocating the ore box transversely, a frame mounted above the ore box, rakes extending from the frame into the ore 35 box, impeller blades pivotally and loosely mounted in front of the rakes and adapted to swing away from the rakes on the backward motion and against the rakes on the forward motion, and rolling pairs of side 40 legs for supporting and reciprocating said frame longitudinally and horizontally.

2. An ore concentrator comprising a platform, posts fixed vertically upon the platform, crosspieces connecting the upper ends 45 of the posts, adjusting screws mounted vertically through the centers of the crosspieces, an ore concentrator box, timbers crosswise of the ore box and under the ore box, rollers carried by the ore box and resting upon the 50 timbers and running transversely, rods extending upwardly from the ends of the timbers, and second timbers connecting the upper ends of the rods and connected to the adjusting screws, so that by manipulating 55 the adjusting screws the ore box may be raised or lowered.

3. An ore concentrator comprising a platform, posts fixed vertically upon the platform, crosspieces connecting the upper ends 60 of the posts, adjusting screws mounted vertically through the centers of the crosspieces, an ore concentrator box, timbers crosswise of the ore box and under the ore box, rollers carried by the ore box and resting upon the 65 timbers and running transversely, rods ex-

tending upwardly from the ends of the timbers, second timbers connecting the upper ends of the rods and connected to the adjusting screws so that by manipulating the adjusting screws the box may be raised or 70 lowered, a shaft mounted longitudinally of the ore box and below the ore box, cam brackets extending downwardly from the ore box, and eccentric cams upon the shaft and engaging the cam brackets so as to reciprocate the ore box transversely by the 75 rotation of the shaft.

4. In an ore concentrator, a platform, gear racks fixed to the platform, segmental gears fitting upon the gear racks, arms secured to the segmental gears and having sets of downwardly inclined notches extending from their side edges, one set above another, a reciprocating frame having studs extending from its sides and fitting in the 80 set of notches, so that the frame may be raised bodily by raising the studs from one set of notches to the next, a link connected to the upper end of one arm, a crank connected to the link, and means for rotating 85 the crank to reciprocate the frame back and forth endwise.

5. A concentrating apparatus comprising a pulp or material box; means upon which the box is mounted for rectilinear movement in a horizontal plane; means for actuating the box with to and fro motions; an organized agitating and raking mechanism also mounted for movement; means for supporting the said mechanism for rectilinear 95 movement in a horizontal plane and substantially parallel to the path of movement of the concentrating box; and means for actuating the said mechanism, whereby the raking depth is maintained constant during 100 operation.

6. A concentrating apparatus comprising a pulp or material box; means upon which the box is mounted for straight linear movement in a horizontal plane; means for actuating the box with to and fro motions; an organized agitating and raking mechanism, means for supporting the said mechanism for straight linear movement in a horizontal plane and substantially parallel to the path of movement of the concentrating box; means for actuating the said mechanism; and carriers for vertically moving the box 110 to vary the depth of immersion of the agitating and raking mechanism.

7. A concentrator comprising a concentrating box having a feed end and a discharge end and frames on which the box is movably supported, means for reciprocating said box transversely, a frame mounted above the box, agitating means on said frame extending into the material being treated, means for reciprocating said frame longitudinally, impeller blades pivotally mounted on said frame to one side of said agitat- 125 130

ing means and adapted to swing away from said agitating means on the backward motion and against the same on the forward motion of said frame, and means for raising and lowering said box to vary the raking depth of said impeller blades.

8. An ore concentrator including a frame, rakes mounted on said frame, impeller blades pivotally and loosely mounted on said frame in front of said rakes, and reciprocating means adapted to swing said impeller blades away from said rakes on the backward motion and against said blades on the forward motion.

9. An ore concentrator comprising an ore trough, a frame mounted above said ore trough, rakes mounted on said frame and depending into said ore trough, impeller blades pivotally and loosely mounted on said frame in front of said rakes, and reciprocating means adapted to swing said impeller blades from said rakes on the backward motion and against said rakes on the forward motion.

In testimony whereof we have signed our names to this specification.

EVERETT A. WILLIAMS.
ALBERT H. WARD.
